VISITORS' SPEAKING DEVICE FOR JAILS

George Edward Oliver, Brooklyn, N. Y.

Application September 28, 1937, Serial No. 166,090

14 Claims. (Cl. 189—5)

This invention relates to a visitors' speaking device for jails and the like and has for an object to provide a tamper and bullet proof device which is arranged to prevent passage of materials between the prisoner and the visitor.

Another object is to provide an efficient, convenient and dependable device of the above type. Various other objects and advantages will be apparent as the nature of the invention is more fully disclosed.

Although the novel features which are believed to be characteristic of this invention will be more particularly pointed out in the claims appended hereto, the invention itself may be better understood by referring to the following description, taken in connection with the accompanying drawing forming a part thereof, in which a particular embodiment of the invention has been shown for purposes of illustration.

Referring to the drawing:

Fig. 1 is a longitudinal section through a speaking device embodying the present invention;

Fig. 2 is an end elevation showing the mouth of the speaking device; and

Fig. 3 is a section taken on the line 3—3 of Fig. 1.

In the following description and in the claims certain specific terms are used for convenience in designating various details of the invention. It is to be understood, however, that these terms are to be given as broad an interpretation as the state of the art will permit.

Referring to the drawing more in detail, the invention is shown as comprising a pair of speaking channels 10 and 11, located on opposite sides of a partition 12 which separates the prisoners' space from the visitors' space. The partition 12 is provided with a window 13 of bullet proof glass or the like through which the prisoner and visitor may be seen.

In the embodiment shown a horizontal shelf 14 extends outwardly on both sides of the partition 12 below the window 13. This shelf supports flared housings 15 which are mounted on opposite sides of the partition 12 and form the speaking channels 10 and 11. The inner ends of the housings 15 are located in alignment with an opening 17 below the window 13 in the partition 12. At the larger or outer end, each housing 15 is provided with a circular flange 22 which is attached to a frame 18 supported by the shelf 14 and attached thereto by suitable means, such as screws 19 and clamping bars 20. The frame is also attached to the partition 12 at a point above the housing 15 by means of rivets 21 and forms a

complete cover which prevents access to any part of the speaking device. It will be noted that the rivets 21 are concealed by the frame 18 and that the screws 19 are concealed by the shelf 14. The ends of the shelf 14 may be closed by depending members 14a so that there is no possibility of either the prisoner or the visitor removing the device in the short time available. The housing may, of course, be mounted in other ways, such as by brackets extending from the partition 12, 10 in which case the shelf 14 may be omitted, or the closure for the device may not be complete provided supervision is exercised to prevent tampering. In the form shown the housings are supported by the frame 18 and may be removed 15 by dismantling the same. They may, if desired, be also attached to the partition 12 at their inner ends in which case the outer support may be omitted.

The outer end of the housing 15 is covered by a screen 30 of suitable material, preferably bullet resistant, such as wire mesh which is of sufficiently close weave to prevent passage of any solid material. The opening 17 is covered on each side by a screen which comprises a perforated steel plate 32 covered by a wire screen 31 of fine mesh. This screen 31 may be compacted by rolling or pressing so as to strengthen the wires at their intersections and also to reduce the size of the openings therein. In the form shown 30 a pair of such screen assemblies are mounted on opposite sides of the partition 12 with the wire screens 31 toward the partition and held by rivets 16, one assembly being associated with each of the housings 15. It is to be understood 35 that the construction of the two housings 15 is identical, one of the devices extending into the visitors' space and the other device extending into the prisoners' space. The screens 30 are inclined so as to receive sound waves from a 40 point somewhat above the speaking device and corresponding to the normal positions of the prisoner and visitor.

The screens 30 and 31 are so disposed that it is practically impossible to thread even the finest 45 wire through the device. The apertures in the two plates 32 may be out of alignment so that direct passage through the two plates is prevented. In some instances the screens 31 may be omitted and a bullet proof perforated plate or 50 plates substituted therefor on both sides of the partition or a single plate or screen assembly may be mounted within the opening 17. The screens 30, of course, need not be inclined as shown although this arrangement provides a maximum 55

audibility and at the same time avoids a straight path through the device. The screens 31 or plates 32 may also be made of bullet resistant material if desired.

5 In the form shown, the lower side of the outer portion 15a of the housing 15 is substantially horizontal and the inner portion 15b is somewhat inclined toward the partition 12. In order to prevent passage of fluids through the device an 10 aperture 35 is provided in the plate 32 communicating with the opening 17 and extending to the visitors' side of the device so as to discharge any fluid on to the shelf 14 in the visitors' 15 space. An aperture 36 may be provided in this shelf adjacent the aperture 35 so as to discharge such fluid on to the floor if desired.

It will be noted that the above construction permits free passage for sound waves between the prisoner and visitor, but prevents passage of 20 any liquid or solid materials therebetween. If it is attempted to pass liquids they are immediately discharged on the visitors' side and do not reach the prisoner. An electric alarm system may also be used to warn of any attempt to pass 25 objects through the device. It is to be understood that the form thereof may be changed in various particulars and that a particular embodiment has been shown for purposes of illustration only. Various changes and modifications 30 may be made therein as will be apparent to a person skilled in the art. The invention is only to be limited in accordance with the following claims when interpreted in view of the prior art.

What is claimed is:

35 1. A visitors' speaking device for jails or the like, comprising a partition dividing the prisoners' space from the visitors' space, said partition having a speaking aperture formed therein and a pair of housings mounted on opposite sides 40 of said aperture to form speaking channels, said devices having their free ends covered by metal screens and having additional screens at their inner ends on opposite sides of said speaking aperture.

45 2. A visitors' speaking device for jails or the like, comprising a partition dividing the prisoners' space from the visitors' space, said partition having a speaking aperture formed therein, a screen covering said speaking aperture, housings 50 extending from opposite sides of said screen into the visitors' space and prisoners' space, respectively, to form speaking channels.

55 3. A visitors' speaking device for jails or the like, comprising a partition dividing the prisoners' space from the visitors' space, said partition having a speaking aperture formed therein, a screen covering said speaking aperture, housings extending from opposite sides of said screen into the visitors' space and prisoners' space, respectively, to form speaking channels and a bullet 60 resistant metal screen covering the free end of each housing.

65 4. A visitors' speaking device for jails or the like, comprising a partition dividing the prisoners' space from the visitors' space, said partition having a speaking aperture formed therein, a screen covering said speaking aperture, a flared housing extending in an upwardly inclined direction from each side of said screen into the visitors' space and prisoners' space respectively to 70 form speaking channels, and an inclined bullet resistant screen covering the free end of each housing.

75 5. A visitors' speaking device for jails or the like, comprising a partition dividing the prison-

ers' space from the visitors' space, said partition having a speaking aperture formed therein, a screen assembly secured to each side of said partition and covering said speaking aperture, each screen assembly comprising a perforated metal plate and a wire screen disposed thereover. 5

6. A visitors' speaking device for jails or the like, comprising a partition dividing the prisoners' space from the visitors' space, said partition having a speaking aperture formed therein, a screen assembly secured to each side of said partition and covering said speaking aperture, each screen assembly comprising a perforated metal plate and a wire screen disposed thereover, a flared housing extending outwardly from each 15 of said screen assemblies and a bullet resistant metal screen covering the free end of each of said housings.

7. A visitors' speaking device for jails or the like, comprising a partition dividing the prisoners' space from the visitors' space, said partition having a speaking aperture formed therein, a screen assembly secured to each side of said partition and covering said speaking aperture, each screen assembly comprising a perforated metal 20 plate and a wire screen disposed thereover, said wire screen being compacted to strengthen the same and to reduce the size of the apertures 25 therein.

8. A visitors' speaking device for jails or the like, comprising a partition dividing the prisoners' space from the visitors' space, said partition having a speaking aperture formed therein, a screen assembly secured to each side of said partition and covering said speaking aperture, each screen assembly comprising a perforated metal plate and a wire screen disposed thereover, a flared housing extending outwardly from each of said screen assemblies and a bullet resistant metal screen covering the free end of each of said 30 housings and means to prevent passage of liquid through said housing comprising an aperture in said partition communicating with said speaking aperture and adapted to discharge fluid therefrom outwardly into the visitors' space. 40

9. A visitors' speaking device for jails or the like, comprising a partition dividing the prisoners' space from the visitors' space, said partition having a window through which the visitor and prisoner may be respectively seen, a shelf extending 50 on opposite sides of said partition, a speaking aperture in said partition above said shelf, a screen assembly mounted on each side of said partition and covering said aperture, a flared housing extending outwardly from each of said screen assemblies in an upwardly inclined direction and an inclined frame attached to said shelf and to said partition to support the free end of said housing. 55

10. A visitors' speaking device for jails or the like, comprising a partition dividing the prisoners' space from the visitors' space, said partition having a window through which the visitor and prisoner may be respectively seen, a shelf extending 60 on opposite sides of said partition, a speaking aperture in said partition above said shelf, a screen assembly mounted on each side of said partition and covering said aperture, a flared housing extending outwardly from each of said screen assemblies in an upwardly inclined direction and an inclined frame attached to said shelf and to said partition to support the free end of said housing and an aperture in said partition below said housing to discharge fluid onto the shelf on the visitors' side of said partition. 70

11. A visitors' speaking device for jails or the like comprising a partition dividing the prisoners' space from the visitors' space, said partition having a speaking aperture formed therein, a screen covering said speaking aperture, a flared housing extending from said screen into one of said spaces to form a speaking channel and a screen covering the free end of said housing, said second screen being out of alignment with said first screen so as to prevent direct passage of objects therethrough.

12. A visitors' speaking device for jails or the like comprising a partition dividing the prisoners' space from the visitors' space, said partition having a speaking aperture formed therein, a screen covering said speaking aperture, a flared housing extending in an upwardly inclined direction from said screen into one of said spaces to form a speaking channel and an inclined screen covering the free end of said housing.

13. A visitors' speaking device for jails or the like comprising a partition dividing the prisoners' space from the visitors' space, said partition having a speaking aperture formed therein, a screen

covering said speaking aperture, housings extending from opposite sides of said screen into the visitors' space and prisoners' space respectively to form speaking channels and screens covering the free ends of said housings, said last screens being out of alignment with said first screen whereby a direct passage of objects therethrough is prevented.

14. A visitors' speaking device for jails or the like comprising a partition dividing the prisoners' space from the visitors' space, a shelf extending on opposite sides of said partition, a speaking aperture in said partition above said shelf, a screen covering said speaking aperture, a flared housing extending in an upwardly inclined direction from each side of said screen into the visitors' space and prisoners' space respectively to form speaking channels and screens covering the free end of each housing, said last screens being out of alignment with said first screen whereby direct passage of objects therethrough is prevented.

GEORGE EDWARD OLIVER.
